(57) **CLAIM**

The ornamental design for tool stand, as shown and described herein.

DESCRIPTION

FIG. 1 is a perspective view of the tool stand of the present invention with the support arms closed and the handles lowered.

FIG. 2 is a front view of the tool stand of the present invention.

FIG. 3 is a back view of the tool stand of the present invention.

FIG. 4 is a top view of the tool stand of the present invention.

FIG. 5 is a bottom view of the tool stand of the present invention.

FIG. 6 is a left end view of the tool stand of the present invention; and,

FIG. 7 is a right end view of the tool stand of the present invention; and,

FIG. 8 is a perspective view of the tool stand of the present invention with the support arms open and the handles raised. The broken lines depict environmental subject matter only and form no part of the claimed design.
